UNITED STATES PATENT OFFICE.

EDWARD W. B. NOWLAND, OF ST. LOUIS, MISSOURI, ASSIGNOR OF ONE-HALF TO
EDWARD NOWLAND, JR., OF ST. LOUIS, MISSOURI.

STEERING APPARATUS FOR FREIGHT-CARRYING BARGES.

1,356,218.

Specification of Letters Patent.

Patented Oct. 19, 1920.

Application filed July 28, 1920. Serial No. 399,523.

To all whom it may concern:

Be it known that I, EDWARD W. B. Nowland, a citizen of the United States, and a resident of St. Louis, State of Missouri, have 5 invented certain new and useful Improvements in Steering Apparatus for Freight-Carrying Barges; and I do hereby declare the following to be a full, clear, and exact description of the invention, such as will 10 enable others skilled in the art to which it appertains to make and use the same.

My invention relates to an improvement in steering apparatus for freight carrying barges, the object being to facilitate the maneuvering of a tow so that the power of the tow boat may be utilized in pushing while 15 the steering is done by rudders at the front of the tow and rear of the tow boat operated by steering mechanism on the latter, and it 20 consists of a tow boat having steering rudders at its stern, and a barge lashed thereto and having steering rudders at its bow the rudders on the barge and tow boat being controlled by steering mechanism on the 25 latter.

It further consists in certain details of construction and combinations of parts as will be more fully explained and pointed out in the claims.

30 In the accompanying drawings, Figure 1 is a view in side elevation of a tow boat and a barge, showing my improvement applied thereto. Fig. 2 is a view in plan of the same. Fig. 3 is a rear end view, and Figs. 35 4 and 5 are views of a false bow for a barge.

10 represents a tow-boat which may be of the type now in general use for towing barges, or it may be especially designed for the purpose, and carrying propelling means 40 (not shown) operated by an engine in the usual and well known manner. This boat 10 is provided at its stern, which is squared as shown with twin rudders 11, the stems 12 of which are coupled together by a bar 45 13 connected preferably at its center to the tiller line 14. The tiller line passes at the stern of the boat around sheaves 15—15 adjacent both sides of the boat and thence up to the steering drum 16 having the steering 50 wheel 16^a. This steering mechanism is preferably driven by steam steering gear (not shown) but may be actuated by hand.

Barges 17 are to be coupled or lashed to the boat 10 in the usual manner, and the 55 barge at the front and center of the fleet

is provided at its front end with rudders 18. In the drawings I have shown one barge lashed at its rear end to the front end of the tow-boat 10, but I would have it understood that my invention contemplates the use of 60 more than one barge arranged in tandem form or side by side as is now customary.

The rudders 18 at the bow of barge 17 are arranged in pairs as shown in Fig. 2, and are connected by the cross-bar 19 connected 65 to the tiller line 20. The stems 21 of the rudders 18 are mounted in and carried by the bearings 22 which may be detachably secured to the bow of the barge and be readily detachable for use on the barge which occupies the front of the fleet in line with the tow-boat 10.

The tiller lines 20 pass around sheaves 23 at the bow of the barge and are guided by the sheaves 24 adjacent the stern of the latter and pass from thence around sheaves 25 at the side of tow-boat 10 and under guides 25^a located below the steering drum 26. This drum is located in line with steering drum 16 and close to the latter, and is provided 75 with a steering wheel 26^a adapted to be actuated by hand. The two steering wheels and their drums are located in the pilot house of the tow-boat 10 and are sufficiently close so that both may be operated simultaneously, but independently of each other by a pilot, in the event of an emergency, and the shafts of the two drums 16 and 26 or the drums themselves may be connected by the clutch 27 actuated by the lever 28. 90

In Fig. 2 the clutch sections are shown disconnected so that the steering drums may be actuated independently, but by shifting the movable section 27 of the clutch to the position shown in dotted lines, both drums will 95 be actuated simultaneously and operate the rudders at the bow and at the stern. By using steam steering gear on the tow-boat and providing a coupling or clutch for the two drums the rudders at the stern of the 100 tow-boat and the bow of the barge may be operated by the steam steering mechanism, or if necessary to manipulate the rudders at the bow of the barge independently of the rudders 11 at the stern of the tow-boat, the 105 latter rudders may be actuated by the steam steering gear and the bow rudders by hand.

The bearings 22 carrying the rudders 18 and stems 21 may be removable and thus adapted for attachment to the front barge of 110

the fleet in the event such barge is not provided with rudder mechanism, but some barges may not be adapted for the attachment of the rudder mechanism, and in such cases I use the false bows 29 which latter are shaped at their rear ends to make a close fit with the barge and carry the rudders 18^a at their front ends, the false bow being provided with snubbing posts 30 whereby it may 10 be lashed to the barge. These false bows are provided with water compartments (not shown) which, when filled or partly filled with water, cause the bow to sink sufficiently to enable its stern to be warped under the 15 bow of the barge, the stern of the false bow being designed to conform to the shape of the bow of the barge.

This false bow is provided with sheaves 23^a and 24^a for guiding the tiller lines back 20 to the sheaves on the barge to which the bow 29 is attached.

It will of course be understood that if the front barge be in advance of other barges the tiller lines will be guided on each of the 25 latter back to the tow-boat.

Various slight changes might be made in the details of construction of my invention without departing from the spirit thereof or limiting its scope and hence I do not wish to 30 restrict myself to the precise details herein set forth.

Having fully described my invention what I claim as new and desire to secure by Letters-Patent, is:

35 1. The combination of a tow-boat having a rudder at its stern and steering mechanism for actuating the same, a barge in advance of said tow-boat and provided with a rudder at its bow, a steering drum on the tow-boat

and tiller lines leading from the rudder on 40 the barge to the steering drum on the tow-boat.

2. The combination of a tow-boat having a rudder at its stern and steering mechanism for actuating the same, a second steering 45 drum on said boat, clutch mechanism for connecting said drums, a barge in advance of the tow-boat and provided with a rudder at its bow, and tiller lines leading from said bow rudder to the second steering drum on 50 the tow-boat.

3. The combination of a tow-boat having a rudder at its stern, two steering drums on 55 said boat, one of said drums being connected with the rudder at the stern, a barge in advance of the tow-boat, a false bow for said barge, a rudder at the front end of said false bow and tiller lines leading from said bow rudder to the other steering drum on the tow-boat.

4. The combination of a tow-boat having a rudder at its stern, two steering drums on 60 said boat, one of which is connected with said rudder, a clutch for connecting the two drums whereby they may be moved in unison, a barge in advance of said tow-boat, a false bow for said barge, a rudder at the front of the false bow and tiller lines leading 65 from the bow rudder to the other steering drum on the tow-boat.

In testimony whereof, I have signed this specification in the presence of two subscribing witnesses.

EDWARD W. B. NOWLAND.
